ATTORNEY

UNITED STATES PATENT OFFICE.

HENRY FRANCIS KEIL, OF BRONXVILLE, NEW YORK.

BRACKET-CLAMP.

1,035,967.

Specification of Letters Patent. Patented Aug. 20, 1912.

Application filed May 16, 1910. Serial No. 561,648.

To all whom it may concern:

Be it known that I, HENRY FRANCIS KEIL, a citizen of the United States of America, and a resident of Bronxville, in the county 5 of Westchester and State of New York, have invented a certain new and useful Bracket-Clamp, of which the following is a specification, the same being a full, clear, and exact description of the invention, such 10 as will enable others skilled in the art to which it appertains to make and use the same.

This invention relates to a supporting piece or combination of pieces of moderate 15 projection generally springing from a vertical surface, and particularly to projecting metal pieces fastened to a wall or other surface, as a support for some object, and provided with self-acting clamping devices 20 constructed and arranged to support rods or other supporting devices.

This invention consists of a peculiar construction and arrangement of parts herein- 25 after described and illustrated in the drawings which accompany and form a part of this specification, and in which—

Figure 1 represents a plan view of brackets provided with my bracket clamp; Fig. 2 is a side elevation of the same; and 30 Fig. 3 is a plan view; Fig. 4 an end elevation; and Fig. 5 a side view of my bracket clamp.

Like letters of reference indicate like 35 parts in all the views.

Referring particularly to the drawings, A denotes a wall or other suitable surface to which the bracket is to be attached, secured to which wall are bracket supports, as A, with which are engaged brackets consisting of an upper member B with a preferably upturned end F, and a lower member G suitably secured to the member B, as by a rivet E, the other end of the member G being preferably screw threaded, as at 45 K. A nut N working on the thread K serves to hold the member G in an adjustable relation, and the bolt H operates as a means of attachment between the member B and the bracket support A.

The bracket clamp C consists of a U-shaped resilient body portion α preferably made of spring metal and having laterally or sidewise extending foot portions c which

are curved inwardly in order to grasp the retaining member B, whereby a self-acting 55 clamping device is formed. The said body portion is ordinarily made with a circular or concave recess b, extending transversely across the same. The foot portions c of the said clamping devices are ordinarily slit, as 60 at e, in order to afford a dual clamping device, whereby a better grip is obtained, the members of the preferably bifurcated foot portions c serving to adapt themselves to any inequalities there may be in the thickness 65 of the bracket member B thereby affording a differential spring grip or clamp action of each part of the two dual members C.

In practice, as many of the clamping devices as it may be desired to use are snapped upon the members B of a pair of brackets, and are securely held in the required positions by the resilience of the clamps. The cross bars D may then be placed in the recessed portions b of the clamping devices, 75 in order that articles of any desired character may be supported thereby.

The clamping devices may be slid along the members B, or, if desired, may be detached therefrom without the use of any screws or other adjusting or releasing devices.

I wish it to be understood that I do not desire to be limited to the exact details of 85 construction shown and described, for various modifications will occur to a person skilled in the art.

What I claim as my invention is:—

A metal bracket clamp comprising a bed 90 plate to rest on the upper face of a bracket and having resilient gripping means and having an inverted U-shaped central part made with a recess formed with four spaced bearing edges, and therebelow positioned 95 horizontal portions extending outwardly from each side thereof to form one engaging means with the bracket, and two adjacent and aligned integral members turned downward to form the horizontal portions 100 at each side of the clamp to form a second engaging means with the bracket and consisting of a pair of differential spring gripping or clamp members one located at each side of the clamp, the free edges of the said 105 pair of downwardly extending parts being

turned inwardly in order to grasp the lower face of the bracket to form a third engaging means with the bracket and to adapt the clamp to be snapped upon the bracket at will and to be retained thereon by the resilience of the metal.

In testimony of the foregoing specifica-

tion I do hereby sign the same in the city of New York, county and State of New York this 18th day of April, 1910.

HENRY FRANCIS KEIL.
